UNITED STATES PATENT OFFICE.

WILLIAM TERRY, OF PEARL CITY, ILLINOIS.

WHEEL HOLDER OR SUPPORT.

SPECIFICATION forming part of Letters Patent No. 747,101, dated December 15, 1903.

Application filed September 8, 1903. Serial No. 172,322. (No model.)

To all whom it may concern:

Be it known that I, WILLIAM TERRY, residing at Pearl City, in the county of Stephenson and State of Illinois, have invented certain new and useful Improvements in Wheel Holders or Supports, of which the following is a specification.

This invention relates to that class of wheel holders or supports which are more particularly adapted for use when it is desired to grease or oil wagon-axles; and it primarily consists of an adjustable bracket member which is adapted to be self-supporting on the wagon-axle and which will easily and positively hold the wheel in position without manual assistance and which is so arranged relatively to the wagon-axle that the wheel can be easily and readily slipped over the axle to the holder, and vice versa.

The invention primarily seeks to provide a device of this character of a simple and economical construction and which will readily and effectively serve its intended purposes.

With other objects in view, which will hereinafter be apparent, the invention consists in certain novel construction and combination of parts, all of which will be first described in detail and then specifically pointed out in the appended claims, reference being had to the accompanying drawings, in which like numerals and letters of reference indicate like parts in all of the figures, and in which—

Figure 1 is a rear elevation of the wagon-wheel with my invention in position ready for use. Fig. 2 is a similar view, the wheel being removed from the axle onto the holder. Fig. 3 is a longitudinal section thereof. Fig. 4 is a perspective view of the holder removed. Fig. 5 is a perspective view thereof, the parts being separated.

In the drawings, 1 designates the wagon-axle, and 2 the wagon-wheel, all of which may be of any approved construction, as they *per se* form no part of my present invention.

My improved wheel-holder A consists of two main parts *a* and *b*, one of which, *a*, has an elongated horizontally-extending portion *a'*, having loops or guides *a²* to receive the elongated portion *b'* of the other member, *b*, which is susceptible to adjustment in the loops or guides *a²*. The portion *a* also has a vertically-extending portion *a³*, having a hook

a⁴ at its lower end, and the said vertically-extending portion *a³* is disposed at right angles to the elongated portion *a'*, as clearly shown in Figs. 4 and 5 of the drawings.

a⁵ designates a Z-shaped bend in the elongated loop-carrying portion *a'* of the member *a* to avoid contact between the portion *a¹⁰* of the member *a* and the elongated portion *b'* of the member *b* to prevent the binding of the parts. The inner member *a* is preferably formed of a continuous flat strip, to which the loops may be welded or attached in any desired manner. The member *b*, however, is preferably constructed of the flat elongated portion *b'* for coöperating with the flat elongated portion *a'* of the member *a* and adapted for sliding adjustment in the loops or guides *a²* to shorten or lengthen the support, and the said portion *b'* merges with the vertically-disposed portion *b²*, preferably circular in cross-section, and the portion *b²* merges with the second horizontally-disposed portion *b³*, also circular in cross-section, and which terminates in a U-shaped end member *b⁴* for fitting over the threaded portion *1^a* of the axle 1, and the portion *b³* is disposed parallel to the portion *b'* and serves as a continuation of the axle 1 when the holder is in position, for a purpose presently explained.

So far as described the operation of my invention can best be explained as follows: The wagon is "jacked" up out of contact with the ground by any suitable jack *J* and the nut then removed in the usual manner. The holder is then placed in position with the hook *a⁴* taking under the inner portion of the axle between the wheel and wagon-body, with the elongated members *a b* passing between the spokes of the wheel and with the U-shaped end resting on the threaded portion *1^a* of the axle 1 and flushed with the smooth or bearing portion *x* of the axle, (see Fig. 3,) the holder being mounted in the vertical plane, as shown. The wheel is now slipped off from the axle 1 onto the portion *b³* of the member *b*, as clearly shown in Fig. 2, to permit of greasing the axle as desired. After the axle has been greased the wheel is again slipped from the portion *b³* onto the axle 1 into the position shown in Fig. 1, when the support may be removed and the nut applied in the usual manner.

From the foregoing description, taken in connection with the accompanying drawings, it will be seen that I provide a support which can be easily and quickly adjusted to its operative position and which will readily and effectively serve its intended purposes.

While I am aware that heretofore wheel-supports have been provided by means of which a wheel may be slipped over the axle 10 onto the holder, yet they do not provide a self-supporting holder, as disclosed by my application.

From the foregoing description it is thought the advantages and complete operation of my 15 invention will be readily understood by those skilled in the art to which it appertains.

Having thus described my invention, what I claim, and desire to secure by Letters Patent, is—

- 20. 1. A wheel-holder comprising an L-shaped member formed of a horizontal portion and a vertical portion, the latter including an integral hook for engaging the vehicle-axle, the horizontal portion having guide-loops, and a 25 U-shaped member, one arm of which is adapted to slidably engage with the guide-loops on the L-shaped member and the other arm thereof having its free end formed to rest upon the axle-spindle end, as set forth.
- 30. 2. A wheel-holder of the character stated, comprising in combination with the L-shaped member formed of a horizontal portion provided with integral guide-loops and including a laterally-bent portion adjacent the angle thereof, the vertical portion of said L-shaped member terminating in a hook for engaging the vehicle-axle, and a U-shaped member composed of a flat portion b' and a 35 round portion at right angles thereto, said 40 round portion being bent at right angles to itself to form a wheel-receiving portion b³

parallel with the flat portion of the said member, said wheel-receiving portion and the vertical portion and the flat portion of the second U-shaped member, all lying in the same 45 vertical plane, the said wheel-receiving portion terminating in a cup-shaped end adapted to fit over the threaded end of the axle-spindle for the purposes specified.

3. A holder comprising in combination with an L-shaped member a, having a horizontal portion a' and a vertical portion terminating in a hook, said horizontal portion a' having integral loops or guides, of a U-shaped member composed of a flat portion b', and a round 50 portion at right angles thereto, said round portion being bent at right angles to itself to form a wheel-receiving portion b³ parallel 55 with the flat portion of the member said wheel-receiving portion, said vertical portion 60 and said flat portion of the second member all being held in the same vertical plane.

4. A holder comprising in combination with an L-shaped member a, having a horizontal portion a' and a vertical portion terminating in a hook, said horizontal portion a' having integral loops or guides, of a U-shaped member composed of a flat portion b', and a round portion at right angles thereto, said round portion being bent at right angles to itself to 65 form a wheel-receiving portion b³ parallel 70 with the flat portion of the member said wheel-receiving portion said vertical portions and said flat portion of the second member all lying in the same vertical plane, said wheel-receiving portion terminating in a cup-shaped 75 end adapted to fit over the threaded end of the wagon-axle, for the purposes specified.

WILLIAM TERRY.
